UNITED STATES PATENT OFFICE.

GERHARD LINDBORG, OF ERIE, KANSAS.

NOZZLE.

1,051,135.

Specification of Letters Patent. Patented Jan. 21, 1913.

Application filed April 16, 1912. Serial No. 691,091.

To all whom it may concern:

Be it known that I, GERHARD LINDBORG, a citizen of the United States, residing at Erie, in the county of Neosho and State of Kansas, have invented certain new and useful Improvements in Nozzles, of which the following is a specification.

The nozzle which is the subject of the present invention is designed more particularly for spraying or distributing sulfuric acid employed in refining lubricating oils, and its object is to provide a novel and improved construction which will deliver a fine spray and which is constructed to operate as an atomizer.

In order that the invention may be better understood, reference is had to the accompanying drawing in which—

Figure 1 is a front end view of the nozzle. Fig. 2 is a central longitudinal section, and Fig. 3 is a cross-section on the line 3—3 of Fig. 1.

Referring specifically to the drawing, 5 denotes the main body of the nozzle, the 25 same being flared at its outlet end 6. The opposite or inlet end of the nozzle is contracted and has an inlet to which is connected an air-supply pipe 7. The inlet is a bore 8 made in the rear end of the nozzle body 5, and said end, inside the nozzle body, has a small nozzle 9 the bore of which is a continuation of the bore 8. The mouth or discharge end of the nozzle 9 is contracted and points toward the flared outlet end 6 35 of the nozzle-body 5. The nozzle 8 is located centrally within the nozzle-body 5 and discharges lengthwise therethrough toward the flared outlet end thereof.

Extending into the main body 5 is a nozzle 10 which is arranged at an angle to the nozzle 9 and delivers the sulfuric acid, said nozzle pointing downward and having its mouth or discharge end located slightly in advance of the mouth of the nozzle 9. The 45 nozzle 10 may be formed integral with the top of the nozzle-body 5, and the latter has a nipple 11 for connection of the acid supply-pipe 12, said nipple being in line and communication with the bore of the nozzle 10.

Beneath the mouth of the nozzle 10 is located a deflector 13 comprising a plate extending from the nozzle 9 in the direction of the outlet end 6 of the nozzle-body 5.

The plate extends from the mouth of the nozzle 9 below the outlet aperture thereof, and dips down from this point and then extends forward with an upward incline. The plate has a sufficient width to hold the acid discharged thereonto, and its top surface 60 has longitudinal corrugations 14. The nozzle 9 and the plate 13 may be formed integral with the nozzle-body 5, and the front end of the plate is braced by a fin 15 extending from the nozzle-body. 65

In operation, air under suitable pressure, is discharged by the nozzle 9 past the mouth of the nozzle 10, which produces suction in the latter and induces a discharge of the acid therefrom, the action being similar to 70 an atomizer. The acid dropping down on the plate 13 is blown along the same by the air issuing from the nozzle 9 and is discharged in the form of a spray from the outlet end 6 of the nozzle-body 5, the latter 75 directing the spray to the place of application so that the spray will be delivered at the proper place. The corrugations 14 serve to regulate the size of the drops.

The entire structure will be made of lead 80 so that it will not be affected by the acid, and it is preferably made in one piece as shown.

I claim:

1. A distributing nozzle comprising a 85 main body having an inlet and an outlet, a nozzle connected to the inlet and discharging in the direction of the outlet, a deflector comprising a plate extending forward from the mouth of the nozzle in the direction of the outlet, and said plate being depressed at the nozzle mouth and thence extending forward with an upward incline, and a second nozzle discharging into the main body toward the depressed portion of 95 the deflector and having its mouth located adjacent to and arranged at an angle to the mouth of the first-mentioned nozzle.

2. A distributing nozzle comprising a main body having an inlet and an outlet, a 100 nozzle connected to the inlet and discharging in the direction of the outlet, a deflector comprising a plate extending forward from the mouth of the nozzle in the direction of the outlet, and said plate being depressed at the nozzle mouth and thence extending forward with an upward incline, a 105 second nozzle discharging into the main

body toward the depressed portion of the deflector and having its mouth located adjacent and arranged at an angle to the mouth of the first-mentioned nozzle, and a fin extending from the nozzle body on the inside thereof, and supporting the forward end of the aforesaid deflector plate.

In testimony whereof I affix my signature in presence of two witnesses.

GERHARD LINDBORG.
